P. PERRY.

Car Brake.

No. 18,516.

Patented Oct. 27, 1857.

UNITED STATES PATENT OFFICE.

PHILANDER PERRY, OF TROY, NEW YORK.

OPERATING RAILROAD-BRAKES.

Specification of Letters Patent No. 18,516, dated October 27, 1857.

To all whom it may concern:

Be it known that I, PHILANDER PERRY, of the city of Troy, in the county of Rensselaer and State of New York, have invented a new 5 and useful improvement in that kind of railroad-car brake heretofore made wherein the weight of the car-body alone is applied to press brake-rubbers against the tops of the car wheels to retard the motion of the car, 10 the weight of the truck-frame being constantly sustained by the journals of the car-axles; and I do hereby declare that the following is a full, clear, and exact description of my invention, reference being had to the, 15 annexed drawings, making a part of this specification, in which—

Figure 1 is a longitudinal, sectional elevation of one of the trucks of a car, with part of the platform or car-body; and of the 20 means which I employ to shift any required portion of the weight of the car-body on and off the brake-rubbers;—also showing my mode of arranging springs to prevent jolting and jarring of the car-body while the 25 brake-rubbers are pressed upon the car-wheels by its weight;—the section being made at the line $z\ y$ in Fig. 2, and viewed in the direction pointed by the arrow x ;— and Fig. 2 is a transverse sectional elevation 30 of the same,—the section being made at the line $w\ v$ in Fig. 1, and seen in the direction indicated by the arrow w .

The same letters refer to like parts in both figures; and the arrows thereon indicate the 35 directions in which the parts move.

My improvement is to be applied to the common eight-wheeled passenger and freight cars in use, which have springs, A, between the journal boxes, B, and the truck-frame, 40 C; and which have the body or platform, D, mounted on the truck-frame either with, or, without, intervening springs to prevent jarring, or pendent bearings to allow lateral movement, of the car-body. In the drawings, annexed, the platform, D, rests upon the truck-frame, without intermediate 45 springs.

E, E, are the usual bearings to keep the car-body from rocking sidewise.

50 F, F, are the car-wheels.

G is the king bolt.

H, H, are the brake-rubbers;—one being arranged over each car-wheel, and each shaped internally to fit the tread of the 55 wheels. These rubbers are firmly united together in pairs, corresponding with the sets

of wheels, by bridges, I, as shown; and it is upon these rubbers that more or less of the weight of the car-body is shifted whenever the speed of the car is to be forcibly retarded. 60 Springs, J, lift the rubbers from the wheels when not overcome by the weight of the car-body.

In Fig. 1 the car is running in the direction pointed by the arrow t ,—with the brake 65 rubbers pressed against the wheels; but in Fig. 2 the rubbers are seen lifted up.

Stops, K, are firmly secured to the truck-frame to limit the upward movement of the brake-rubbers; and to keep the rubbers in 70 place, and from turning with the car-wheels when forced against the latter.

M is the brakeman's common hand-wheel, having a fast-pulley or drum N.

Directly over each bridge I, of a pair of 75 rubbers, a strong screw, O, is firmly secured, in a vertical position, to the bottom of the car-body. A nut, P, is fitted to run up and down on each screw, and extends down to the bridge I. The nuts P are pulleys; and a 80 chain, Q, is wound on them all, and also upon the pulley N of the hand-wheel in such manner that the brakeman, by turning the hand wheel in one direction, runs the nuts down on the screws O so as to first push the 85 brake-rubbers down upon the car-wheels, and then gradually transfer any required portion of the weight of the car-body, from the truck frame, and consequently from the springs A, to the brake-rubbers, and thereby, 90 to the top surface of the car-wheels; and, by turning the hand-wheel in the other direction, runs the nuts up on the screws so as to release the brake-rubbers, and, car-wheels.

Instead of arranging but one nut and 95 screw to work each pair of brake-rubbers, I use two to each bridge whenever desirable,—one near each end, as at s and s' ;— the screws being all worked simultaneously by the hand-wheel and chain, to brake, and 100 unbrake. The hand-wheel-chains may extend around and operate all the brake screws of the two trucks of the car.

By the use of the sets of nuts and screws arranged upon the bottom of the car-body, 105 worked by the hand-wheel-chain, and operating the pairs of brake-rubbers, as set forth, I attain advantageous results which I believe have not been heretofore secured by the use of analogous devices; for by this construction the brakeman, by means of the common hand-wheel, shifts any required

portion of the weight of only the car-body, upon and off from the pairs of brake-rubbers, arranged over the wheels as described, with equal ease, whichever way the car is running;—no force being exerted, in shifting the weight of the car-body on and off the brake-rubbers, tending to press the brake-rubbers in the same direction with, or in the opposite one, to that in which the 10 car-wheels are turning,—as there is in S. K. Goodale's model (at the Patent Office,) which has wedges sliding longitudinally in the bottom of the car-body to shift the weight of the car-body on and off a frame of 15 four brake-rubbers, over the car wheels.

To prevent jolting and jarring of the bodies of passenger and other cars while the brake-rubbers remain pressed against the tops of the car-wheels by the weight of the 20 car-body, alone, I arrange springs at any suitable place or places between those parts of the rubbers which bear against the wheels, and the bottom of the car-body, in such manner that whatever part of the 25 weight of the car-body is shifted upon, or off from the brake-rubbers is transmitted thereto or therefrom by or through these springs; which are seen in the drawings at R, arranged in the bridges, I, between the 30 lower bar, a, which is firmly secured to the brake-rubbers, and the upper one, b, which slides up and down between guides c, c, fast

on the brake-rubbers.—the upward motion being limited by the stops, d, on the brake-rubbers. These springs, R, also serve to 35 lessen the difficulty, or increase the ease, with which the weight of the car-body is brought to bear upon the brake-rubbers;—for the springs yield under pressure so that the hand-wheel is turned farther, to bring a given weight upon the rubbers, when the springs are employed in the manner set forth, than when they are absent. 40

What I claim as my invention and desire to secure by Letters Patent is, 45

1. The use of the sets of nuts and screws arranged upon the under side of the car-body, worked by the hand-wheel and chain, and operating upon the pairs of brake-rubbers, as herein described, for the purposes 50 specified.

2. I also claim arranging springs, R, between the bottom of the car-body and the brake-rubbers, as described; so as to prevent jolting or jarring of the car-body while 55 its weight presses the brake-rubbers upon the top of the car-wheels, and also to facilitate the application of the brake-rubbers, as specified.

PHILANDER PERRY.
